United States Patent

Des. 241,506
Patented Sept. 21, 1976

241,506

CHAIN AND HOOK LOCK

Peter J. Condos, 626 Jamestown Road,
Burbank, Calif. 91504

Filed Nov. 7, 1975, Ser. No. 629,922

Term of patent 14 years

Int. Cl. D8—07

U.S. Cl. D8—137

Fig. 1

Fig. 2

Fig. 2

Fig. 5

Fig. 3

FIG. 1 is a perspective view of a chain and hook lock showing my new design;

FIG. 2 is a front elevational view thereof;

FIG. 3 is a top plan view thereof;

FIG. 4 is a bottom view thereof; and

FIG. 5 is a right-hand, end view thereof.

I claim:

The ornamental design for a chain and hook lock, substantially as shown.
